UNITED STATES PATENT OFFICE.

CHARLES A. FAUTZ, OF NEWARK, NEW JERSEY, ASSIGNOR TO CHARLES C. CHAMPENOIS, OF SAME PLACE.

BUTTON AND STUD.

SPECIFICATION forming part of Letters Patent No. 244,441, dated July 19, 1881.

Application filed May 18, 1881. (Model.)

To all whom it may concern:

Be it known that I, CHAS. A. FAUTZ, a citizen of the United States, residing in the city of Newark, county of Essex, and State of New Jersey, have invented certain new and useful Improvements in Buttons and Studs, fully described and represented in the following specification and the accompanying drawings forming a part of the same.

10 My invention relates to an improvement in the post and the shoe of a button or stud; and it consists in an improved construction for hinging them together, and for simplifying the construction of the shoe and spring, and for strengthening the front plate by means of feet formed in one piece with the post herein described.

15 The improved construction of the post consists in forming it of two thin parallel columns, united at their rear ends by solder to a piece of tube-wire, and formed at their front ends with feet bent parallel to the front plate, to strengthen the plate when soldered thereto.

20 The improved construction of the shoe consists in making it of a disk of metal, which forms a hinged plate to bear against the flattened end of the post, the hinge being formed of a spring-strip attached to the disk at both ends and indented at or near the middle to fit 25 a pin in the rear end of the post, the spring being in all cases formed in one piece with the disk by punching slots at its sides and stamping it into the desired form.

25 My invention will be understood by reference to the annexed drawings, in which—

Figure 1 is a rear view of a cuff-button provided with my improvements. Fig. 2 is a section on line $x-x$ in Fig. 1. Fig. 3 is a view similar to Fig. 2, with the shoe shown in 30 dotted lines in its position for insertion. Fig. 4 is a side view of the entire button; Fig. 5, a plan of the blank for making the post P; and Fig. 6, a rear view of the shoe D.

40 A is the front or ornamental side of a cuff button, to which my invention is shown as applied, and which may be made in any desired style. The post I have devised is adapted to strengthen such a front, if made of metal, by the soldering of its bent feet to the rear side 45 of the front plate.

P is the post; B, a slot in its rear end, to which the shoe is hinged.

C is a pin arranged across the slot and secured to the post, to form the pivot of the shoe D.

55 E is the hinge, formed of a spring-strip of metal stamped out of, or struck up from, the back D and attached at both its ends to the shoe, and being an integral part thereof, the middle of the strip being shown indented at e to fit the pin C. The hinge or spring E is also pushed to one side of the plate D, so that the latter may bear upon the end of the post or its side when the bend at e embraces the pin C. The spring thus draws the shoe firmly against 60 the post and holds it in the desired position securely.

65 In Fig. 2 the shoe is represented as opened, or in position for use, while in Fig. 3 a dotted outline of the shoe is shown turned parallel 70 with the post for insertion into a button-hole.

75 The shoe described may be used with any post adapted to receive the spring E and pin C; but I have devised one of peculiar form for use in the construction of fine gold jewelry where the saving of metal is important. To secure the greatest lightness and strength combined, I make the post of two thin columns kept apart by the hinge-pin, and provided with feet, which serve to stiffen the front A when 80 soldered to its inside. To make the post I form by suitable tools a blank of sheet metal like that shown in Fig. 5, the piece being of the width required in the post and long enough to form the height of the post when doubled, 85 as well as the projecting feet F. By suitable tools I bend the blank to the form shown in Fig. 3, a slot being provided in the middle to form the notch shown in the rear of the post in Fig. 4, at B, and a pin, C, or piece of tube-wire in which a pin can be inserted is then 90 soldered in the loop of the blank at the middle of the slot, and the rear end of the post is finished by filing off flat, as shown in Figs. 2 and 3.

95 From the above description it will be seen that my improved post and shoe may each be made of a single piece of metal, and that the soldering of the tube-wire in the end of the post affords a convenient means of introduc- 100

ing and removing the pin C when desired for repairs.

The shoe D is exceedingly strong, simple, and durable, and not easily deranged when in use.

For studs an ornamental or convex cap can be applied to the rear of the shoe by any desired means, and the spring hinge thus concealed from view.

10 I am aware that buttons have been made with a spring extending across the shoe for a purpose similar to that for which I use it; but in such buttons as those patented in July, 1872, as No. 129,904, and No. 224,386 of 1880, 15 the spring construction permitted the sliding of the shoe across the end of the post, and could not therefore be stamped out of a slot in the shoe in the simple manner I have devised. This construction I am enabled to employ by restricting the movement of the shoe solely to tipping on its hinge to a position parallel with the side of the post. I do not therefore claim any construction adapted to slide across the rear end of the post, as do those 20 referred to above; but,

Having described the real construction and

operation of my devices, I claim the same, as follows:

1. In combination with the post of a button or stud, the hinged shoe, constructed as 30 herein shown and described, adapted to bear against the flattened end of the post, and hinged thereto by an indented spring made integral with the shoe and attached thereto at both ends, the whole arranged to operate solely 35 by a tipping movement, and prevented from sliding by the attachment of the spring at both its ends, substantially as and for the purpose described.

2. The post P, having slot B and pin C in 40 its rear end, and flattened to fit the shoe, as herein described, in combination with the shoe D, formed in one piece with the spring E, and hinged to the pin C by an indentation in the spring, substantially as herein set forth. 45

In testimony whereof I have hereunto set my hand in the presence of two subscribing witnesses.

CHAS. A. FAUTZ.
